UNITED STATES PATENT OFFICE.

ALBERT D. GOODELL, OF SHELBOURNE FALLS, ASSIGNOR TO THE LANGDON
MITER BOX COMPANY, OF MILLER'S FALLS, MASSACHUSETTS.

MITER-BOX.

SPECIFICATION forming part of Letters Patent No. 544,092, dated August 6, 1895.

Application filed April 10, 1895. Serial No. 545,158. (No model.)

To all whom it may concern:

Be it known that I, ALBERT D. GOODELL, a citizen of the United States, residing at Shelburne Falls, in the county of Franklin and State of Massachusetts, have invented new and useful Improvements in Miter-Boxes, of which the following, together with the accompanying drawings, is a specification sufficiently full, clear, and exact to enable persons skilled in the art to which this invention appertains to make and use the same.

The objects of my present invention are to render the miter-box more efficient and convenient for service, to provide means for automatically supporting the saw-guides and saw in elevated position when lifted and for readily releasing the same by simple and easy action, to afford means whereby the adjustment-locking devices or thumb-latch may be operated by the saw-hand without releasing the grip on the saw-handle, to afford a conveniently-adjustable stop for regulating the depth of kerf as desired, and to perfect and improve the structure in its various parts and actions, as more fully hereinafter explained, the particular subject-matter claimed being definitely specified in the summary.

In the drawings, Figure 1 is a front view, and Fig. 2 a plan view, of a miter-box, embracing the features of my invention. Fig. 3 is a vertical sectional view showing the swing-bar, adjusting and saw-guiding devices, and means for supporting the saw-guides elevated. Figs. 4 and 5 are transverse sections of the swing-bar and grooved gib or rest. Fig. 6 is a vertical section of one of the saw-guides, its support, and adjusting devices. Figs. 7, 7^a, and 8 show the detail of the automatic elevating and stop devices, and Fig. 9 is a section of the saw and stud thereon.

Referring to parts, A denotes the horizontal frame or bed, and B the upright back for supporting the work; C, the center-bolt or axis, and D the swing-bar, having thereon the cylindrical sockets D', carrying the upright vertically-movable saw-guides E in usual manner. The bed is provided with a front circular arc A' and a smaller arc a, each concentric with the axis C. The front circle has a graduated scale a² of degrees and parts of degrees upon its top and notches d d' in its

lower edge, into which the thumb lever F engages for retaining the swing-bar and saw-guides at the principal adjustment positions, as for sawing miter, octagon, and square angles.

G indicates a gib or rest, comprising a straight bar grooved in its top and bottom surfaces and extending radially from the circle a to the circle A' and resting thereon, and preferably having a point or index e, that lays over the graduated scale a², for denoting the degree of angular adjustment. This gib is arranged upon the top of a longitudinal upward projection or fin D² fixed upon a swing-bar D, which fin enters the under groove (see Fig. 4) and serves to retain said gib in proper lateral relation while allowing it up and down looseness. A rod or bolt h, threaded into or attached to the gib, extends down through a lever or block H' at the under side of the swing-bar, and a screw H, having a handle for turning the same, is provided for forcing down the block H' and clamping the gib G and swing-bar to the circles firmly at any position of adjustment when it is desired to have the saw-guides fixed at position. The manner of arranging the gib in connection with its clamping-screw and lever and the graduated scale and indicating-point on the end of the gib are features of my invention, the object of which mechanism is to adjust the angle to any intermediate degree between the points at which the latch mechanism engages.

Another feature of my invention consists in providing means for automatically retaining the saw elevated by simply raising it to its highest position. For this purpose there is combined with the saw-guiding posts E swinging catch plates or bars I, that engage with lugs or studs J, fixed on the sides of the sockets D', which catches automatically drop into engagement when raised. These catches are best made as angle-levers pivoted to the head of the saw-guides at i, with their arms I' connected one with the other by a bar I², which serves as a handle for simultaneously disengaging both catches by simply raising said lifter-bar I', which swings the catches off from their engaging studs or notches at J.

The plates I are longitudinally slotted at

J' and the screw or stud J passes through said slot. The lower end of the slot is offset and a lug m formed at one side thereof, so that when the saw-guides E and plates I are elevated by lifting the saw the lug m is automatically carried over the stud J and retains the parts elevated, as indicated by dotted lines, Fig. 3, until the end of the catch-plates are released from the studs J, which is done by simply lifting the bar or link I² until it takes the weight of the saw and guides, and thereby lowering the saw upon the work.

The catch is best formed by offsetting the slot at the lower end of the latch-bar; but in some instances, if preferred, it might be a notch or lug and the outer edges of the latch-bar to engage suitable lugs or notches on the socket for retaining the saw elevated, as indicated by dotted lines at m², Fig. 7.

In connection with the catches I arrange stops, which can be adjusted to any position for stopping the downward movement of the saw. K K indicates these stop-studs, arranged upon the boss or plates I, preferably with a screw-threaded shank passing through the slot J' in the plate and provided with a thumb-nut on the outer side thereof, (see Fig. 8,) said stop-studs being adjustable up and down the slot above the end or shoulder of the saw-guide socket D' and to be fixed at any desired position of adjustment for stopping the downward movement of the saw-guides and saw at a given distance above the bed to facilitate sawing tenons or work in which it is desired that the saw-kerf should not pass completely through the stock. These stops K can be fixed at the upper ends of the slots when the saw is to completely cut off the stock. These adjusting-stops can be arranged in the slots of the catch-bars, or a separate slide-bar can be attached to the guide-post for carrying the studs K. The preferable method is that shown.

The thumb-latch or lever F for engaging the notched circle and holding the swing-frame D with its saw-guides at the regular miter angles—square, hexagon, octagon, &c.—is, in accordance with my invention, provided with an upwardly-extending arm F', located in front of the saw-guide at one side of the slot and adjacent to the side of the saw S, which latter I provide, at or near its handle S', with a shoulder, lug, or stud t, that is adapted to engage or make contact with said arm F' for operating the latch F to release the swing-bar D when the saw is run forward or at extreme advanced position. Thereby the operator can, while holding the saw, by tilting the saw, unlatch and adjust the swing-frame without releasing the work in his other hand. This permits the convenient shifting of the angle from right to left while holding the piece of molding or stock on the bed.

For adjusting the position of the saw-guiding posts as the saw is worn narrower by filing I arrange a screw n at the bottom of

the socket, the body of said screw being threaded into the bar D parallel with the axis of the socket, and its flange or head n' extends beneath the socket-opening, so that the foot of the saw-guide E strikes thereon when in depressed position. (See Fig. 6.) Adjustment is effected by turning the screw in or out, as required.

P P indicate auxiliary guides, each comprising a slotted plate with a dependent end that can be adjusted over the bed for supporting the work away from the back B when more acute angles are desired than the radial adjustment of the swing-bar affords. The guide P is mounted on a bracket or support R at the top and rear of the back plate B and is held at adjusted position by a thumbscrew Q. For use the guides can be set over the bed, as shown at the left in Fig. 2, and when not in use turned back out of the way, as shown at the right on Fig. 2.

What I claim as my invention, and desire to secure by Letters Patent, is—

1. In a miter-box mechanism, the combination, with the bed-frame having the larger and smaller concentric circular arcs, and the swing-bar carrying saw-guides and pivotally connected with said frame; of the grooved gib or rest its ends respectively supported upon said circular arcs, its under groove embracing the top of an upwardly projecting fin fixed on said swing-bar, the lever-block beneath said bar, clamp-bolts connecting said block and grooved gib, and the hand-screw for depressing said lever-block and binding the parts upon said arcs, for the purpose set forth.

2. In a miter-box mechanism, the combination, of the bed-frame having its circular arc provided with a graduated face-plate thereon, the swing-bar pivoted to said frame and carrying the saw-guides, the grooved gib mounted upon an upwardly projecting portion of said swing-bar, radial to said arc, the index point on the end of said gib, and means substantially as described for clamping said gib and swing-bar upon the arc for retaining their adjustment at any position, as set forth.

3. The combination, with the vertically movable saw-guides, and their supporting sockets, of catch-bars or plates pivotally connected with the heads of said saw-guides, and engaging lugs and notches, respectively disposed on said catch-bars and sockets, that engage for sustaining said saw-guides elevated, said catch-bars adapted to swing said lugs and notches into engagement, automatically, when the saw is lifted from the work and said saw-guides raised to high position, substantially as set forth.

4. The combination with the vertically movable saw-guides and their supporting sockets, of the angle-lever catch-bars pivoted to the saw-guides and having notches or lugs at their lower ends, the studs for engaging therewith fixed on the sockets, and the lifting-bar pivotally connected with the inwardly

projecting arms at the top of said catch-bars, for the purposes set forth.

5. In a miter-box mechanism, the combination of the swing-bar having upright sockets thereon, the saw-guides vertically movable in said sockets, the catch-bars respectively pivoted to the saw-guide heads, said catch-bars having longitudinal slots therein and fitted with engaging notches or lugs at their lower ends, the catch-studs fixed on said sockets for engagement of said catch-bars, and the thumb-nut stop-studs adjustably secured upon said catch-bars for contact with the shoulder of the sockets, for the purpose set forth.

15 6. The combination with the bed-frame, its

notched circular arc, and the swing-frame carrying the saw-guides, of the thumb-latch pivoted within the swing-frame, its rear end engaging with the notch in said circular arc; 20 said thumb-latch having its forward arm extended upward in front of the saw-guide-socket adjacent to the side of the saw, and a saw having a projecting stud at its handled end adapted for contact with said thumb-latch, for the purpose set forth.

Witness my hand this 6th day of April, A. D. 1895.

ALBERT D. GOODELL.
